CONVERTIBLE FILING MACHINE

Leighton A. Wilkie, Minneapolis, Minn.

Application August 28, 1937, Serial No. 161,366
In Great Britain April 20, 1937

3 Claims. (Cl. 29—76)

This invention relates to abrading machines and more particularly to hand machine tools adapted to be held in, or supported by, the hands of the operator during use.

5 One of the objects of the invention is the provision of a new and improved power operated filing machine that may be held in the hands of the person using the same during the operation of the machine.

10 Another object of the invention is the provision of a new and improved endless, hand type, power driven filing machine of novel construction that is adapted to be held in the hand or hands of the operator while using the device.

15 A further object of the invention is the provision of a new and improved hand power operated tool that may be readily converted into a power driven, upright, filing machine.

20 A still further object of the invention is the provision of a new and improved hand filing machine having a power unit mounted therein and the parts so constructed and arranged that the machine may be held normal to the work or may be canted or held at an angle thereto during the 25 operation of the machine.

25 Another object of the invention is the provision of a new and improved portable power filing machine that is simple in construction, effective in operation, easily assembled, composed of relatively few moving parts, and that may be converted into an upright filing machine that is simple in construction, effective in operation, easily assembled, composed of relatively few moving parts, and that may be converted into an 30 upright filing machine that cannot be supported by the hands of the operator.

35 Other and further objects and advantages of the invention will appear from the following description taken in connection with the accompanying drawings in which

40 Fig. 1 is a side elevation of the device, with parts in section and parts broken away;

Fig. 2 is a section on the line 2—2 of Fig. 1;

Fig. 3 is a section on the broken line 3—3 of

45 Fig. 1;

Fig. 4 is a vertical section on the line 4—4 of Fig. 1;

Fig. 5 is a section on the line 5—5 of Fig. 1;

Fig. 6 is a side elevation of the device as applied to an attachment for converting the apparatus into a conventional filing machine;

Fig. 7 is a section on the line 7—7 of Fig. 6;

Fig. 8 is a detailed view showing the means for connecting the file band;

50 Fig. 9 is a vertical section similar to Fig. 5 but

showing a modified form of filing elements and backing member; and

Fig. 10 is a plan fragmentary view of adjacent ends of the file elements showing one form of interlock.

5 It is common practice to employ upright stationary filing machines in machine shop work but in such machines, it is necessary to bring the work to the machine for operating on the same. The present invention seeks to provide a tool that 10 is light enough and compact enough that it may be moved to the work manually. The present invention is in the nature of a hand tool and is adapted to be used as such.

Furthermore, in certain types of work, or work 15 on certain objects or articles, a manually portable filing device may be used to advantage while on others an upright stationary filing machine is more desirable. The present invention provides filing mechanism that may be readily converted from a portable hand tool to an upright 20 filing machine at the will of the operator and with the expenditure of a minimum of time and labor, as will presently appear.

25 Referring now to the drawings, the reference character 10 designates generally the filing tool or apparatus which comprises a frame or casing element 11 having, what for convenience of description will be termed, a top portion 12 and a pair of outwardly or downwardly extending arms 30 or arm portions 13 and 14. The form of the casing is approximately that of an inverted U, having a laterally extending flange 9 about each end and across its top portion, see Figs. 3 and 4. The space 15 between the arms constitutes what 35 may be termed the throat of the tool or apparatus.

40 A pair of alined pulleys 16 and 17 are mounted on suitable journals 18 and 19, see Fig. 2, which are rigidly connected to the arms 13 and 14.

45 A suitable file element carrier 21 is trained over the pulleys and has its lower run extending across the opening or space 15 for forming a working zone for the file elements. This carrier may be of any flexible construction and, in the form shown, is a metal band 21 to which the file elements 22 are secured. The file elements are secured in any suitable manner as by means of bolts or rivets 23 which engage the central portion of the file elements and suitable openings in 50 the carrier 21. In order that the carrier or band 21 may be opened so as to extend the same through a closed opening for inner filing, it is severed at one point as shown in Fig. 8 and one end is provided with a keyhole slot 24 and the other 55

with a corresponding button 25 for engaging the slot.

The casing or frame 11 is preferably, though not necessarily, open on one side as shown in Figs. 3 and 4 so that access may be readily had to the operating mechanism and for removing the band. A detachable closure may be provided if desired.

A suitable backing member 26 for the working zone of the file elements is provided. Any suitable means may be provided for this purpose. In the form of the construction shown, this backing member is in the form of a straight bar 27 having a channel 28, Fig. 5, for receiving

the band 21 and is deep enough to engage the inner portions of the sides of the file elements 22 as shown in Fig. 5 of the drawings. The bar 27 is provided with a counter channel 29 which is adapted to accommodate the heads of the rivets 23 which secure the file elements to said band. Extending upwardly from each end portion of the bar 26 are attaching lugs 31 by means of which the bar is rigidly attached to the frame or casing 11, as shown in Figs. 1 and 5.

Suitable means are provided for adjusting one or the other of the pulleys 16 and 17. In the form of the construction shown, what will be termed the outer pulley 16, Figs. 1 and 2, is so mounted that it may be adjusted. Any suitable construction may be used for this purpose. In the form of the construction shown, the journal 18 for the pulley 16 is provided with a reduced portion 33 and this reduced portion extends through a slot 34 in the casing 11 and is secured to a sliding block 35 which in turn is mounted in a slideway formed by a flange 36 extending about the opening 34. The slide block 35 is provided with an outwardly extending flange 37 at its forward end which has a screw threaded opening in which an adjusting screw 38 engages, as shown more clearly in Fig. 1 of the drawings. The head 39 of the screw engages in a slot 41, Fig. 2, formed by lugs 42 and 43 on the side of the casing 11 which prevents longitudinal movement of the screw. It will thus be seen that by rotating the screw, the block 35 may be moved to adjust the pulley 16 either inwardly or outwardly for loosening or tightening the file carrier or belt.

Appropriate mechanism is provided for operating the pulleys 16 and 17. Any suitable means may be employed for this purpose, such as a motor, flexible shaft, or the like. In the form of the construction shown, an electric motor 44, 65 mounted in the casing 11 above the pulleys 16 and 17 and adjacent to the inner end thereof, is employed for this purpose. As shown, the armature or shaft of the motor extends longitudinally of the frame and is provided with a worm 45, Fig. 3, which engages a gear 46 which in turn is rigidly secured to a gear 47. The gear 47, through a series of reducing gears 48, 49 and 50, operates the pulley 17 at a reduced speed.

The casing 11 and operating mechanism are of such size and weight that the device may be held in the hands of the operator. Suitable means are provided for holding and guiding the device while in operation. As shown, a detachable handle 51, detachably connected to the power end of the device, is employed for this purpose. Any suitable mechanism may be provided for detachably connecting the handle to the casing. As shown, the handle is provided with a dove-tailed groove 52, see Fig. 2, which is adapted to engage a corresponding dove-tailed pro-

jection 53 on the casing. A spring-pressed latching bolt 54, extending through an opening in the handle attaching portion and engaging a corresponding opening 55 in the end of the casing 11, secures the handle in position. When it is desired to remove the handle, it is only necessary to pull outwardly on the latch 54 and move the handle either upwardly or downwardly to disengage it from the dove-tailed projection 53. A handle member 56, rigidly secured to the frame 10 and extending across the forward side thereof parallel therewith, is also provided for holding the tool, as shown in Figs. 1 and 2.

In the operation of the device, the operator grasps the handle 51 in his right hand and the handle 56 in his left and applies the filing device in the working zone to the work.

It is desirable that the device be so constructed that it may be readily converted into an upright filing machine. Such a construction 20 is shown in Figs. 6 and 7. In order to convert the device into an upright filing machine, a base 57 is provided which has, on its upper surface, extending longitudinally thereof, in a horizontal plane, a dove-tailed groove 58 of the shape and 25 size of the groove 52 in the handle member 51 and in attaching the tool to the base 57, the handle 51 is removed by first disengaging the pin 54 and sliding the handle from the tool, then turning the outer end of the tool upward 30 and sliding the dove-tailed projection 53 in the groove 58 of the base until the pin 59, extending upwardly through an opening in the base and carried by a leaf spring 61, attached to the base as at 62, engages the opening 55 in the end of 35 the casing 11.

The forward end of the base 57 is provided with an upright 63 which has a table 64 adjustably mounted on a shaft 65 at the upper end thereof. The table 64 is provided with a sleeve 40 66 that is slidably mounted on the shaft 65 and is held in adjusted position by a set screw 67. The table is provided with a slot 68 through which the carrier and file elements are adapted to move. The table is of such a height that the 45 working zone of the file elements extends above and below its upper surface, as shown more clearly in Fig. 6 of the drawings.

If desired, the backing member 26 and file elements may be constructed as shown in Fig. 9 60 of the drawings. In this figure, the backing member 69, which corresponds to the backing member 26 of Fig. 1, is provided with a groove 71 for receiving the band 21 and an inward projection 72 on the file elements 73. Each of the file elements 73 is rabbeted at each side thereof to form the projection 72 for engaging in the groove 71 and also to form lateral extensions 74 and 75 which engage over and bear against the sides of flanges 76 of the backing member 69. The parts 60 are so constructed that the backing member 69 is no wider than the file elements 74, as clearly shown in Fig. 4 of the drawings. The backing member 69 is provided with attaching tabs or ears the same as that already described. The backing member 69 may be substituted for the backing member 26 when desired simply by removing the bolts or screws that hold the member 26 in position.

While the file band may be run in either direction as desired, by the proper motor or gearing, it is understood that when the tool is of the type that may be converted into an upright stationary machine the run of the belt across the working zone will be moving rearward when in operation 75

so that when it is converted into a filing machine of the stationary type, the belt at the working zone will be moving downward. Unless the motor is reversible, with the mechanism shown, the file belt of the tool at the working zone will be moving rearward, thus causing the tool to tend to move forward and it is held from moving forward by the operator.

The file elements may be of any suitable form 10 in cross section and their ends may interlock. In the form shown in Fig. 10, the adjacent ends of the file elements have a V-shape interlock, that is, the forward end of one element may be provided with a V-shaped projection for interlocking with a corresponding recess in the rear end of the preceding element as shown more particularly in Fig. 10. As shown, the rear link 22 is provided with a V-shaped projection 11 which engages a corresponding recess 13 for holding 20 these ends in alignment. The links may be of any desired length, as shown, they are substantially two inches in length but other lengths may be employed.

By omitting the cover from the casing or frame, 25 free access may be had to the band for removing the same. Furthermore, the omission of this cover and the provision of the space 15 in the side of the casing permits the operator to cant the tool for filing at an angle when desired.

It is thought from the foregoing taken in connection with the accompanying drawings, that the construction and operation of my device will be apparent to those skilled in the art, and that minor changes in size, shape, proportion and details of construction may be made without depart-

ing from the spirit and scope of the appended claims.

I claim as my invention:

1. A convertible filing tool and filing machine comprising a frame, movable abrading means carried by said frame, power operated mechanism on said frame for operating said means, a supporting base, and means including one element of a dove-tail joint on one end of said frame for attaching a handle thereto to form a hand tool or 10 for attaching said frame in an upright position to said base to form an abrading machine.

2. A convertible hand supported, power operated filing tool and machine comprising a frame, movable filing mechanism on said frame, a motor 15 on said frame for operating said mechanism, a handle, an interlocking connection comprising a dove-tail projection on said frame for attaching said handle to said tool, a base, means on said base for cooperating with said projection for securing said frame in upright position on said base, a table, and means for supporting the same above said base, said table having a slot through which said filing mechanism is adapted to be moved by said motor.

3. A convertible hand supported power operated tool and filing machine comprising a frame, movable filing means on said frame, power operated mechanism for operating said filing means, a base, and means on the inner end of said frame 30 for detachably attaching a handle to said frame or for detachably connecting said frame to said base in an upright position for forming a filing machine.

LEIGHTON A. WILKIE. 35
